UNITED STATES PATENT OFFICE.

HAMILTON POE, OF ST. LOUIS, MISSOURI.

FEED-WATER HEATER.

SPECIFICATION forming part of Letters Patent No. 334,192, dated January 12, 1886.

Application filed November 11, 1884. Renewed December 17, 1885. Serial No. 185,968. (No model.)

To all whom it may concern:

Be it known that I, HAMILTON POE, of St. Louis, Missouri, have made a new and useful Improvement in Feed - Water Heaters for 5 Steam-Boilers, of which the following is a full, clear, and exact description.

This is an improvement in that class of feed-water heaters which introduce the water in the form of spray into the boilers.

10 It consists partly in the means for regulating the inflow of the feed-water, partly to the means by which the position of the valve used in regulating the inflow of the feed-water is determined, partly to the mode of balancing 15 the feed-water valve, and partly to the means used in spraying the feed-water.

The annexed drawings, making part of this specification, illustrate the improvement.

Figure 1 is a side elevation of the improvement, the boiler-shell being shown in section; 20 Fig. 2, a vertical section on the line 23 of Fig. 1, the feed-water valve being seated; Fig. 3, a similar section, the feed-water valve being unseated.

25 The same letters of reference denote the same parts.

The feed-water, as indicated by the arrow *x*, Fig. 1, is introduced through the pipe *A*. It flows into the chamber *B*, and thence past 30 the valve *C* into the boiler *D*. Only that portion of the boiler immediately connected with the improvement is exhibited. The valve seats at *e*, near the lower end of the plug *E*. This plug is screwed into the boiler-shell *d*, 35 and, if desired, a jam-nut, *F*, may be screwed from the interior of the boiler onto the plug and against the boiler-shell. The jam-nut, however, in many instances is omitted. The plug *E* is made hollow to admit the feed-water 40 from the chamber *B*, and it serves to support the chamber *B* and the other parts of the feed-water device. It may, and is so shown, be an extension of the shell *b* of the chamber *B*. The valve *C* is attached to the stem *C'*. The stem 45 extends upward through the plug and chamber, passing out through the chamber-shell *b*, upward through or past the cross-bar *G*, and at its upper end having a weight, *H*, attached to it. The cross-bar *G* is upheld by the rods 50 *I I*, which in turn are supported by the lugs *b' b'* upon the shell *b*. A spring, *J*, encircles the stem, its lower end resting upon the cross-

bar *G* and its upper end bearing upward against a vertically-adjustable shoulder, *K*, upon the valve-stem, and which is in the form 55 of a nut adapted to be screwed upward and downward upon the valve-stem. By screwing the nut downward upon the valve-stem the spring is compressed, and the valve is adapted to open less readily, and by adjusting the nut 60 higher up upon the valve-stem the valve is adapted to open more readily. This feature of the improvement is of especial value when a battery of boilers is being supplied from a common pipe, and each boiler is supplied with 65 one of the present feed-water devices. In such case the water-pressure varies in the different feed-water devices, and by means of the adjusting mechanism described the various valves can be suitably adjusted to the various 70 pressures. The weight *H* is used to balance the valve against the boiler-pressure. The valve-stem is furnished with a finger, *L*, which rises and falls with the valve-stem and valve. It is adapted to operate, in connection with the 75 fixed graduated arm *M*, upon the chamber *B*, the position of the finger upon the graduation indicating the position of the valve with reference to its seat. Whether the valve is opened or closed or how far it is opened can therefore be readily determined by noticing the 80 position of the finger upon the graduation.

Hitherto in such feed-water devices it has been customary to employ within the boiler a large inverted-cup-shaped plate, termed a 85 "breaker," against which the feed-water is directed, and in consequence broken into spray. Such a plate is objectionable in that it requires, by reason of its size, to be introduced into the boiler through a large opening, such as the man-hole, and which is often remote from the point at which it is desired to attach the feed-water device, and to be upheld from within the boiler in connecting it with the exterior portion of the device. This difficulty is overcome in the present construction 90 as follows: The plug *E*, without enlarging its external diameter, is extended below the valve-seat *e*, and is shaped to form the flange *e'*. The flange extends downward to the level of the 95 valve at its largest diameter when the valve is opened. The feed-water then, after it passes the valve, encounters the flange, and is thereby broken into spray; but, owing to the man-

- ner of forming the flange, all that portion of the feed-water device which needs to be within the boiler can be inserted through the opening made in the boiler-shell to receive the plug E.
- 5 The valve C at its lower end is preferably tapered to a point, as thereby the boiler-pressure is less liable to interfere with the working of the valve.
- I claim—
- 10 1. The combination of the boiler D, the plug E, the chamber B, the cross-bar G, supported substantially as described, the valve C, the

stem C', the spring J, and the shoulder K, substantially as described.

2. The combination, in a feed-water-heater 15 device, of the boiler D, the plug E, having the valve-seat e and the flange e', as described, and the valve C, substantially as described, and for the purpose set forth.

Witness my hand.

HAMILTON POE.
